UNITED STATES PATENT OFFICE.

GEORGE H. KING, OF TROPICO, CALIFORNIA.

NON-CARBONIZING SYSTEM FOR INTERNAL-COMBUSTION ENGINES.

1,247,966.

Specification of Letters Patent. Patented Nov. 27, 1917.

Application filed May 15, 1916. Serial No. 97,697.

To all whom it may concern:

Be it known that I, GEORGE H. KING, a citizen of the United States, residing at Tropico, in the county of Los Angeles and State of California, have invented a new and useful Improvement in Non-Carbonizing Systems for Internal-Combustion Engines, of which the following is a specification.

10 My invention relates to means for preventing the accumulation and deposits of carbon on the pistons and cylinder walls of internal combustion engines and has for its object the provision of such means with additional means for facilitating and increasing the combustion of the fuel by the addition of artificially supplied oxygen to the combustion chambers of the engine.

20 A further object is to provide an arrangement of the several elements of my device which will permit the ready adjustment thereof at easily accessible points about the engine.

25 A further object is to provide means for introducing steam into the fuel intake of the engine by way of the carburetor and intake manifold and means for creating the steam by the utilization of the exhaust from the engine in passage to the engine.

30 A further object is to provide means for connecting the steam supply means with the radiator of the vehicle on which the engine is mounted and for collecting the water derived from the steam and storing the same

35 for use in connection with certain well known oxygen producing chemicals for the purpose of mixing additional oxygen with the steam and introducing the mixture into the combustion chambers of the engine for effecting a more perfect combustion of the fuels.

40 A further object is to provide a trap means in the water chamber in the steam passage for preventing the entrance of the water into the engine cylinders and arranged so that the movement of the vehicle may not displace the water therefrom.

45 A further object is to provide a steam chamber for equalizing the pressure of the steam in the supply means. Other objects will appear in the following detailed description of my invention.

50 Referring to the drawings, in which similar characters of reference indicate the same parts throughout the several views, Figure 1 is a partial elevation of the vehicle to

which my device is applied and showing the engine and related mechanism exposed to view. Fig. 2 is a transverse section of the exhaust pipe from the engine showing the 60 steam heating coils attached thereto. Fig. 3 is a transverse section of the steam chamber. Fig. 4 is a sectional elevation of the steam trap. Fig. 5 is a perspective view of the steam trap cap showing the vent therein. 65 Fig. 6 is a transverse section at the bottom of the steam trap showing the water outlet, and Fig. 7 is a transverse section of Fig. 4 at a point just below the cap.

I will now describe the structure and operation of my device in detail. The radiator 1 of the vehicle is usually provided with an outlet 2 at the bottom or side near the bottom with a pet cock 3 in connection therewith for the purpose of draining off the 70 water, and to this outlet I attach a small caliber pipe 4, as shown in Fig. 1, which extends upwardly in the direction of the engine and has a union 5 inserted at a convenient point to facilitate the attachment 75 thereof. The pipe 4 may, if desirable and convenient, be connected to the pump outlet pipe 6 of the radiator, as shown in broken lines, instead of to the outlet 2, and at a point opposite the exhaust pipe 7 of the 80 engine a coil 8 is formed in the pipe which is attached to the exhaust pipe 7 by means of metallic bands 9 clamped together at the ends by means of screws 10, a packing of asbestos being wrapped around the coil for 85 completely inclosing the coil. The coil of pipe is thus held in close proximity to the exhaust of the engine and the water which rises in the pipe and coil to the level of the water in the radiator is heated and steam 90 is generated therein which rises in the upper end 11 of the pipe which leads to and is connected with a steam chamber 12 suspended from a rod 13 usually provided in vehicles of this character. In the absence of such a 100 rod, however, the steam chamber may be attached at any suitable point and by any suitable means to the dash board or other convenient member of the vehicle, but preferably at a point at or above the top of the 105 radiator.

The steam chamber 12 is preferably cylindrical in form, as shown in Fig. 3, and an internal lug 14 is provided through which the rod 13 is extended for supporting the 110 chamber in position. The water in the radiator, when the engine is hot and in opera-

tion, is usually at or near the boiling point and a certain amount of steam is mixed therein with the water, so that the water from the radiator which rises in the pipe 4, 5 while ordinarily hot and mixed with a certain amount of steam, is further heated by means of the contact of the pipe 4 and the coil 8 with the engine exhaust, and a steam supply is thus created and stored in the 10 steam chamber 12, in which a desired pressure may be at all times had, and a steam gage may be attached to the chamber 12, if desirable, though this is usually unnecessary for the reason that an outlet is provided for the radiator and an excessive or injurious pressure will never be reached.

The steam chamber 12 has an outlet 15 to which is attached a pipe 16 leading to the trap and water chamber 17, a valve 18 being 20 inserted in this pipe which is operable by means of an extended stem 19 through the dash board 20 of the vehicle, and is thus easily within the reach of the vehicle operator. Suitable unions 21 may be inserted at 25 convenient points in the several pipe connections, such as the pipe 11 and also the pipe 16 for the purpose of facilitating the attachment and connection thereof.

The steam trap 17, as shown in enlarged 30 form in Figs. 3, 4, 5 and 6, is composed of an elongated cylinder with a relatively small upper portion 22 and the larger bottom portion 23. A removable cap 24 may be threaded on the upper end of the upper end 22, or 35 otherwise secured thereto, and this cap is provided with a very small vent 25 in the top. A steam inlet 26 is provided in the periphery of the upper portion 22 of the trap which is connected with the pipe 16 40 from the steam chamber 12, and an outlet 27 is provided therein at a point near the top which is connected with a nipple 28. A T fitting 29 is connected at opposite ends with the nipple 28 and a pipe 29' and at the central opening with a depending nipple 30. A 45 valve 31 is attached at opposite points to the nipple 30 from the T 29 and a pipe 32 which terminates at a point beneath and in close proximity to the air intake 33 of the 50 carbureter 34. An additional connection with the engine intake is provided in the pipe 35 attached to the manifold 36 with a valve 37 attached to the pipe 35 and the nipple 29 at opposite points, and a by-pass 55 is thus provided for the passage of the steam from the trap 17 to the combustion chambers of the engine, so that in the event of the inaccessibility of the air intake of the carbureter, or the inconvenience of arranging 60 the pipe 32 in proper relation thereto, the steam may be passed directly into the intake manifold instead of through the carbureter. In some cases it may be desirable to install both of these connections on a vehicle, so 65 that for any reason, a change may be made

in the manner of introducing the steam into the engine, by closing the one or opening the other of the valves 31 and 37.

A water chamber 38 is formed in the enlarged portion 23 of the trap 17 which receives the water condensed from the steam and an outlet 39 is formed in the extreme bottom of the chamber which terminates in the end of the curved lug 40 to which is suitably attached a coil 41 which is wrapped 70 several turns around the periphery of the portion 23 of the trap and at the end is bent upwardly and terminates at a point slightly below the inlet pipe 16 and above the water level in the chamber 38, thus forming a trap 75 for the water and serving also as an overflow therefor, so that an excess of water may be drained off through the coil. It is obvious 80 that the violent shaking or movement of the vehicle will not serve to displace the water from the water chamber 38, and this is desirable, for the water chamber may be used as an oxygen producing chamber, by removing the cap and inserting quantities of oxygen bearing chemicals, such as sodium peroxid 85 or other elements from which the oxygen may be released by contact with the steam and water. The reaction caused by the mixture of the chemicals with the water will 90 cause the release of the oxygen, which when mixed with the steam and discharged from the chamber therewith into the engine combustion chambers will increase the combustion of the fuel.

It will be understood by those skilled in the art that the introduction of the steam alone serves to break up and prevent the carbon deposits in the engine cylinders and on the piston ends and valves, and this being a fact, it should be also understood that the 100 introduction of a sufficient quantity of oxygen, other than that introduced through the carbureter from the air, causes a more perfect combustion of the fuel and the consequent decrease in the quantity of the carbon, 105 inasmuch as more of the heat making elements of the fuel are consumed and less of the carbon, which is a product of combustion, results from the successive explosions 110 of the engine. It is apparent that a practically uniform pressure of steam is maintained in the pipe 16 and trap 17 as well as in the pipes leading to the intake of the engine, and the steam, or steam and oxygen together are sucked into the manifold by the 115 vacuum therein when the engine is in operation, thus affording a constant supply in proportion to the area of the valve passages in the supply pipes, which may be increased or decreased, at will by the operator.

Having thus described my invention, what I claim is:

1. In a device of the character described, the combination with the engine, fuel supply means therefor and the circulating water 130

- means therefor, of means for connecting the fuel supply means and water circulating means for generating and introducing steam into the combustion chambers of the engine, 5 and means connected therewith for generating oxygen for mixture and introduction with the steam, for preventing the deposits of carbon and effecting a more perfect combustion of the fuel.
- 10 2. In a device of the character described, the combination with the engine, fuel supply means therefor and the radiator connected therewith, of means for connecting the radiator with the fuel supply means, includ- 15 ing a heating coil for generating steam, a steam chamber connected therewith for maintaining a uniform pressure in the line, a combined water chamber and trap for extracting the water from the steam and draining it off, means whereby chemicals may be 20 introduced into said water chamber for producing oxygen for mixture with the steam, and valve means for regulating the supply of steam and the mixture of steam and oxygen. 25
3. In a device of the character described, the combination with the engine having fuel intake and exhaust means, and the radiator, of a steam generator attached to said exhaust means and connected with said radiator; a steam line leading therefrom to said intake, including a steam chamber and a trap, valve means in said line for regulating the supply of steam to said intake, and means in said trap for generating oxygen for mixture with the steam. 30
- 35

Signed at Los Angeles, in the county of Los Angeles and State of California, this 8th day of May, 1916.

GEORGE H. KING.
